Specification for Design.

Patented Mar. 23, 1920.

Application filed April 14, 1919. Serial No. 290,101. Term of patent 3½ years.

To all whom it may concern:

Be it known that I, HOWARD E. NAY, a citizen of the United States of America, and resident of Wheeling, county of Ohio, and State of West Virginia, have invented a new, original, and ornamental Design for a Badge, Button, or Emblem, of which the following is a specification, reference being had to the accompanying drawings, in which—

Figure 1 is a face view of a badge, button or emblem showing my new design; and—
Fig. 2 is an edge view of the same.

I claim:

The ornamental design for a badge, button, or emblem, as shown.

HOWARD ERWIN NAY.
